UNITED STATES PATENT OFFICE.

NELSON J. RUSSELL, OF MINNEAPOLIS, MINNESOTA.

ACTUATING MECHANISM FOR GAS-GENERATING MACHINES.

1,138,151.

Specification of Letters Patent.

Patented May 4, 1915.

Application filed February 23, 1912. Serial No. 679,229.

To all whom it may concern:

Be it known that I, NELSON J. RUSSELL, a citizen of the United States, residing at Minneapolis, in the county of Hennepin and 5 State of Minnesota, have invented certain new and useful Improvements in Actuating Mechanism for Gas-Generating Machines; and I do hereby declare the following to be a full, clear, and exact description of the 10 invention, such as will enable others skilled in the art to which it appertains to make and use the same.

My invention relates particularly to gas generating machines adapted for use in 15 generating gas from gasoline, and has for its object to improve the same in the several particulars hereinafter stated.

Generally stated, the invention consists of the novel devices and combinations of 20 devices hereinafter described and defined in the claims.

In the accompanying drawings which 25 illustrate the invention, like characters indicate like parts throughout the several views.

Referring to the drawings, Figure 1 is a view in front elevation showing the improved generating machine; Fig. 2 is a side elevation of the machine with some parts 30 broken away and some parts sectioned; Fig. 3 is a view partly in front elevation and partly in vertical section showing the right hand portion of the machine; Fig. 4 is a detail in vertical section taken on the line 35 $x^4 x^4$ on Fig. 3; Fig. 5 is an enlarged view on the same section as Fig. 4; Fig. 6 is a section taken on the line $x^6 x^6$ on Fig. 5; and Fig. 7 is a section taken on the line x^7 x^7 on Fig. 3.

40 In the type of gas generating machines shown in the drawings, a rotary air supply and compressing drum 1 is arranged to rotate within the water containing tank 2, this being a type of air compressor well known in this art and heretofore frequently 45 employed. For the purposes of this case, it is only necessary to call attention to the fact that in the complete generating apparatus, air is supplied to the carbureter by 50 rotation of the said drum 1. The water tank 2 of this air compressor or air pump is, as shown, supported by a suitable framework made up of front and rear members 3 and 4, and end members 5 and 6. Said 55 frame members at the corners of the frame

structure are rigidly but detachably connected, preferably by suitable bolts 7 which permit the sections of the frame-work to be readily disconnected for the purpose of shipment or storage. As a convenient 60 means for supporting the tank 2 on the framework, the front and rear members 3 and 4 are shown as provided with rest lugs 8 that engage the outwardly projecting flanges of reinforcing angles 9 riveted to 65 the upper edge of the said tank 2. The rotary air supplying drum 1 is provided with a shaft 10, journaled in suitable bearings on the ends of the drum 2, and at one end, projecting and journaled also in the 70 right hand end frame member 6. This projecting end of the said drum shaft 10 is provided with a relatively large sprocket 11 and a relatively small sprocket 12.

75 Journaled in the end frame members 6 and in the transverse tie bar 13 of the frame-work is a counter shaft 14 on which is a windlass drum 15 that is preferably keyed to said shaft. At its left hand end (see Figs. 3 and 7), the windlass drum 15 is 80 provided with a ratchet wheel 16, and at its right hand end, said drum is provided with one or more laterally projecting ratchet teeth 17. Loosely journaled on the shaft 14 adjacent to the ratchet wheel 16 85 is a large sprocket 18 provided with a spring-pressed dog 19 that co-operates with the said ratchet wheel 16. Loosely journaled on the right hand end of the counter shaft 14 is another sprocket 20 and laterally projected ratchet tooth 21 adapted to be engaged with the ratchet tooth 17 of the drum and to be disengaged therefrom, by lateral sliding movements of the said sprocket 20. The said sprocket 20 is shown 95 as provided with a grooved hub 22 with which a shipper lever, not shown, is adapted to engage to move the said sprocket 20 laterally and to set the said sprocket either in an operative or inoperative position, at will. 100

The numeral 23 indicates a mast or column, preferably in the form of a metal pipe, which is detachably connected to the frame-work, being preferably passed through an upper guide lug 24, and with its lower end seated in a pocket 25, both of which elements 23 and 24 are shown as cast integral with the rear frame member 4. A sheave supporting head 26 is supported by the mast 23 being, as shown, provided with an in- 110

verted pocket in which the upper end of the said mast is inserted. Guide sheaves 27 are journaled to the ends of the head 26.

The numeral 28 indicates an operating cable which is passed over the guide sheaves 27, is provided at one end with a heavy weight 29, and at its other end is wound upon and secured to the windlass drum 15.

The numeral 30 indicates a sprocket chain 10 which runs over the alined sprockets 12 and 18.

The numeral 31 indicates a spur gear 15 which is journaled on a trunnion 32 projecting from the upper portion of the right hand frame section 6. The gear 31 carries a small sprocket 33 over which and a large laterally movable sprocket 20 on the shaft 14, a sprocket chain 34 is arranged to run.

The numeral 35 indicates an operating 20 crank, the shaft of which is journaled in the upper portion of the frame section 6 and is provided with a spur pinion 36 that meshes with the gear 31.

With the above described construction, it 25 is obvious that when the weight 29 is raised, it will exert a force which acts through the cable 28, drum 15, ratchet wheel 16, dog 19, sprockets 12 and 18, and chain 30, will rotate the air supplying or compressing drum 1 in the direction of the arrow marked adjacent to said drum on Fig. 2. Also, normally, the ratchet tooth 17 of the drum 15 is free from the ratchet tooth 21 of the sprocket 20, so that the said sprocket 20, 30 chain 34, sprocket 33, gears 31 and 36, and crank 35, stand idle while the said air supplying drum is being rotated in the direction stated, to supply air for the generation of gas. When the weight 29 is to be wound 35 up, the sprocket 20 is moved laterally so that its ratchet tooth 21 will engage the ratchet tooth 17 of the windlass drum, and then by rotation of the operating crank 35, the said drum may be rotated backward or 40 in a direction to wind up thereon, the cable 28 and thereby raise the weight 29. This winding of the weight thus rotates the drum 15 backward without rotating the air supplying drum 1, for the reason that the ratchet wheel 16, under backward rotation, 45 will pass freely under the dog 19 of the sprocket 18. Thus it will be seen that the weight may be raised very quickly and easily at any time without interrupting for more than a few moments the air supplying 50 action of the compressor pump.

In gas generating apparatus of this character, it is a common practice to supply the gasolene as well as air to the carburetor chamber or device by means of a pump. For this purpose I preferably employ a cylinder and piston pump of the character disclosed and claimed in my pending application, S. N. 660,915, filed of date, November 17th, 1911, and entitled, "Pump." My

invention also includes novel connections whereby the piston of this pump will be reciprocated under a minimum of friction from power supplied by the weight utilized to drive the drum of the air compressor. Of 70 the parts of this gasolene pump, the numeral 37 indicates a cylinder structure which, as shown, is suitably secured to the frame section 6, and the numeral 38 indicates the rod of the said pump piston. The upper end of 75 the piston rod 38 is connected by a link 39 to the free end of an arm 40, pivoted at 41 to the said frame section 6. In its free end, the arm 40 is provided with a longitudinal slot 42 in which works the crank pin 43 of 80 the crank disk 44. The crank disk 44 and a sprocket 45 are both, as shown, secured to a short shaft 46 journaled in the upper portion of the frame section 6 (see Fig. 6). A sprocket chain 47 runs over the sprocket 45 85 and over the sprocket 11, heretofore noted, as located on the shaft 10 of the air supplying drum 1. By reference to Fig. 5, it will be noted that the crank disk 44 is provided with a spirally spaced series of perforations 90 48, into any one of which the crank pin 43 may be inserted to thereby afford a vertical throw crank adapted to be adjusted so as to give just the desired amount of gasolene per unit of air supplied by the rotary drum 1. 95 The adjustment of the said crank, therefore, determines the percentage or relative amount of oil and air that will be mixed to produce the gas, and when this percentage or proportion is determined by the setting 100 of the crank pin, that certain per cent. or proportion will be maintained, regardless of whether or not the gas is used slowly or rapidly. Otherwise stated, one rotation of the air supplying drum 1 will supply a predetermined amount of air and will cause a predetermined number of movements of the piston of the gasolene supplying pump and, consequently, the predetermined amount of 105 gasolene for mixture with air. 110

By referring to Fig. 4, it will be noted that the pivotal connection between the link 39 and the arm 40 moves approximately on a vertical line coincident with the projected axis of the piston rod 38. Otherwise stated, the said link 39 moves without any perceptible angularity or deviation from alignment with the piston rod. Hence, in some instances, it may be found practicable to connect the piston rod directly to the free 115 end of the said arm 40.

The pump driving mechanism above described, is simple, generally efficient and highly desirable for use in connection with a gas generating machine of this general 120 character.

The machine is adapted to be easily taken apart and packed in a small space for shipment. As already indicated, the sections of the framework may be easily separated and 125 130

the head 26 may be easily detached from the mast 23 and the said mast easily detached from the said frame. At the same time the machine, when the parts are set up, constitutes a self contained structure adapted to be moved as an entirety, without changing any of the adjustments or relative positions of the parts of the machine. Attention is further called to the fact that when the weight 29 is being wound up or raised, the oil or gasoline supplying pump as well as the air supplying pump or compressor remain idle.

What I claim is:—

- 15 1. A motor for gas generating machines and the like, provided with a motor driven element, comprising a projecting shaft on said motor driven element, a counter-shaft, a windlass drum on said counter-shaft, a sprocket on said counter-shaft adjacent one end of said windlass drum, a sprocket on said projecting shaft, a sprocket chain running over said sprockets, a pawl and ratchet connection between said windlass drum and the adjacent sprocket, a weight, a cable connecting said weight to said windlass drum, a crank driven sprocket on the machine frame, a laterally movable sprocket located on said counter-shaft adjacent the other end of said windlass drum, and a sprocket chain running over the latter noted sprockets, the said laterally movable sprocket and the said windlass drum having coöperating lugs en-
- 20
- 25
- 30

gageable by lateral movements of the said sprocket, substantially as described. 35

2. A motor for gas generating machines and the like provided with a motor driven element, comprising a projecting shaft on said motor driven element, a counter-shaft, a windlass drum on said counter-shaft, a 40 sprocket on said counter-shaft adjacent one end of said windlass drum, a smaller sprocket on said projecting shaft, a sprocket chain co-operating with said sprockets, a pawl and ratchet connection between said windlass 45 drum and the adjacent sprocket, a weight, a cable connecting said weight to said windlass drum, a relatively small driving sprocket on the machine frame, a relatively large gear fixed to said sprocket, a crank driven pinion 50 meshing therewith to drive said gear, a laterally movable and larger sprocket located on said counter-shaft adjacent the other end of said windlass drum, and a sprocket chain coöperating with said driving sprocket and 55 said laterally movable sprocket, the said laterally movable sprocket and the said windlass drum having coöperating lugs engageable by lateral movements of the said sprocket, substantially as described. 60

In testimony whereof I affix my signature in presence of two witnesses.

NELSON J. RUSSELL.
